Specification for Design.

Patented Apr. 26, 1921.

Application filed April 16, 1919. Serial No. 290,615. Term of patent 14 years.

To all whom it may concern:

Be it known that I, JAMES C. MORRISON, a citizen of the United States of America, residing at Highland Park, in the county of Wayne and State of Michigan, have invented a certain new, original, and ornamental Design for a Jar or Similar Container, of which the following is a specification, reference being had therein to the ac-

companying drawing, forming part thereof, in which the figure is a perspective view of a jar or similar container showing my new design.

I claim:

The ornamental design for a jar or similar container, substantially as shown.

In testimony whereof I affix my signature.

JAMES C. MORRISON.
